UNITED STATES PATENT OFFICE.

ERNST LINDNER, OF BROOKLYN, NEW YORK.

DESIGN FOR A GAS-BURNER FIXTURE.

SPECIFICATION forming part of Design No. 27,945, dated December 7, 1897.

Application filed October 22, 1897. Serial No. 656,108. Term of patent 7 years.

To all whom it may concern:

Be it known that I, ERNST LINDNER, a citizen of the United States, residing at Brooklyn, Kings county, and State of New York, have invented and produced a new and original Design for an Incandescent-Gas-Burner Fixture, of which the following is a specification, reference being had to the accompanying drawing, forming a part thereof.

10 The annexed drawing shows a view in elevation of an incandescent-gas-burner fixture embodying my design.

15 The object of my invention is to produce a new and original design for an incandescent-gas-burner fixture; and the invention consists in the configuration or shape of the burner-fixture substantially as illustrated in the drawing.

20 The design for the fixture comprises the cylindrical portion A, with beads a and b, the bead b being of greater diameter than the bot-

tom bead a. Beneath the bead a is a cylindrical portion B of less circumference than the portion A. Surmounting the cylindrical portion A is the dish-like portion C, having 25 a plain upper part c and below the latter a series of narrow elongated slots c'. The dish-like portion C has a rim D, with a series of bent fingers d.

The distinctive feature of the design is the 30 cylindrical portion A, surmounted by the dish-like portion C.

I claim—

35 The design for an incandescent-gas-burner fixture substantially as shown.

Signed at New York, N. Y., this 21st day of October, 1897.

ERNST LINDNER.
